D. McLean.
Sails & Rigging.
No 19,225. Patented Jan 26, 1858.
Fig; 1;

UNITED STATES PATENT OFFICE.

DONALD McLEAN, OF BOSTON, MASSACHUSETTS, ASSIGNOR TO HIMSELF, AND SAMUEL GREEN AND NATHAN AMES, OF SAUGUS, MASSACHUSETTS.

REEFING TOPSAILS.

Specification of Letters Patent No. 19,225, dated January 26, 1858.

To all whom it may concern:

Be it known that I, DONALD McLEAN, of Boston, in the county of Suffolk and Commonwealth of Massachusetts, have invented 5 a new and useful Arrangement of Means for Reefing Topsails from the Deck; and I do hereby declare that the following is a full, clear, and exact description of the construction and operation of the same, reference being had to the accompanying drawings, 10 forming a part of this specification.

Figure 1 is a front view of the apparatus, representing the sail as partially reefed. Fig. 2 is a section showing more fully the 15 application of the rolling supporter, D.

To enable others skilled in the art to make and use my invention, I will now proceed to describe its construction and operation.

20 The mast A; the main-yard F; the top-sail-yard G; the top-sail halyards J, and bolt-rope K, are all similar to those in common use.

B, the revolving jack-yard, is a cylinder, 25 either of wood, or (what I consider still better) of metallic tubing so as to combine the greatest amount of strength with the least amount of weight. The ends of B, as seen in Fig. 1, are furnished with journals 30 passing through, and turning in, the metallic hangers, H,—the latter being bolted, or confined in any suitable manner, to the top-sail yard, G.

S, the sail, is cut like those in common 35 use, but instead of its upper edge, or head-rope being nailed to a fixed jack-yard, it is drawn over the revolving cylinder, B, by means of the reef-lines, C C C, as represented in Fig. 1,—said lines passing down 40 to the deck and made fast to belaying pins.

L L L, are rings, or cringles, fast to the foot-rope of the sail, their object being to

guide the reef-lines, C C C, and pull the sail in such a manner as to prevent its wrinkling.

45 D is a grooved roller, turning freely on the stiff metallic hanger, or staple, I I, whose upper ends are fast in the top-sail yard G. As will be seen in Fig. 2, there are two of these rollers, one front, and the other 50 back, of the sail. The object of the rollers is to support the revolving jack-yard, B, and prevent it from bending, as it otherwise would do, unless it were made too large and heavy. If necessary, several of these rollers 55 may be used, at various distances from the center of the yard.

E is a large central rope sewed fast to the sail. Said rope, as seen in Fig. 1, passes under the roller D, in the groove d, and thereby prevents the sail from slipping laterally. It is obvious that, instead of 60 grooving the roller D, a groove may be made in the revolving jack-yard B, and answer the same purpose.

65 Operation: In order to reef the sail it is only necessary for a man, or men, on deck, to let go the top-sail halyards and simultaneously pull down the reefing lines L L L, when it is obvious that the sail will double 70 over itself, more or less, as may be desired. It is also plain that the sail may be clewed up and furled, in the usual manner.

75 What I claim as my invention and desire to secure by Letters Patent is:—

The arrangement, substantially as described, of the revolving jack-yard, B, and the reef-lines, C, whereby the sail is reefed by simply doubling over itself, instead of being rolled, or tied up.

DONALD McLEAN.

Witnesses:

GEO. H. SMITH,
N. AMES.
